LEATHER STRETCHING FRAME

Ira Milton Jones, Thiensville, Wis.

Application November 2, 1933, Serial No. 696,330

10 Claims. (Cl. 149—21)

This invention relates to improvements in leather stretching frames as used for the stretching and drying of hides and the like.

Leather stretching frames now generally consist of a stiff supporting or border frame preferably formed of tubing to which a perforated metal sheet is attached, the skins or hides to be stretched and dried being attached to the perforated metal sheet by means of toggles which grip 10 the edge of the hide or skin and have hooks to engage in the perforations of the metal sheet.

To insure the best results, it is, of course, essential that the perforated metal sheet be perfectly flat and as a comparatively heavy gauge metal 15 must be used to withstand the strain, it has been difficult in the past to fasten the perforated sheet to the supporting frame without having objectionable wavy or uneven portions in the sheet.

It is, therefore, an object of this invention to 20 provide a novel construction for frames of this general type and a method of making the same by which the application of the perforated sheet is materially simplified and a flat surface is assured.

More specifically, it is an object of this invention 25 to provide a frame structure of the character described and a method of making the same whereby the sheet is put under tension during the assembly of the frame.

Another object of this invention is to provide 30 a frame so constructed that upon forced separation of its two complementary sections, the perforated sheet is placed under tension in all directions.

Another object of this invention is to provide a frame unit of the character described wherein 35 the perforated metal sheet is attached to its supporting or border frame by being welded thereto.

With the above and other objects in view 40 which will appear as the description proceeds, my invention resides in the novel construction, combination and arrangement of parts substantially as hereinafter described and more particularly defined by the appended claims, it being 45 understood that such changes in the precise embodiment of the herein-disclosed invention may be made as come within the scope of the claims.

In the accompanying drawings, I have illustrated 50 several complete examples of the physical embodiment of my invention constructed according to the best modes I have so far devised for the practical application of the principles thereof, and in which:

Figure 1 is a view in elevation of a stretching

frame embodying this invention and illustrating the manner of applying a hide thereto;

Figure 2 is a fragmentary detail view illustrating the means for spreading the border frame sections shown in Figure 1;

Figure 3 is a view illustrating another manner of spreading the border frame sections to apply tension to the perforated sheet;

Figure 4 is a view illustrating the invention in a modified embodiment;

Figure 5 is a view showing the completed frame unit of Figure 4, and the manner in which its sections are placed in tension during the making of the same;

Figure 6 is a detail section view through Figure 15 5 on the plane of the line 6—6;

Figure 7 is a view in elevation of another modified embodiment of this invention; and

Figure 8 is a detail section view taken through Figure 7 on the plane of the line 8—8.

Referring now more particularly to the accompanying drawings in which like numerals indicate like parts throughout the several views, and especially to Figures 1, 2 and 3, the numeral 5 designates a rectangular border frame formed 25 of tubing and comprising two complementary halves or sections 6 and 7. Each section has an elongated side portion 8, end portions 9 and diagonal corner portions 10. The adjacent extremities of the end portions 9 are joined by T 30 shaped fittings 11, the stems of which provide trunnions 12 by which the entire frame may be mounted to swing on its longitudinal axis.

Attached to the border frame 5 is a perforated metal sheet or plate 13, slightly smaller than the 35 inside dimension of the frame. The manner of attaching the sheet to the border frame is such that during assembly of the unit, the sheet is placed under tension. To this end, the corners of the sheet are folded over the diagonal corner 40 portions 10 of the frame sections and riveted down as at 15. Consequently, upon forced spreading of the frame sections 6 and 7, the sheet 13 will be placed in tension in all directions insuring an even flat surface throughout its entire area.

The means to forcibly spread the frame sections 6 and 7 may be as illustrated in Figures 1 and 2. As here shown, the heads 16 of T fittings 11 each have one end riveted or otherwise secured to the end portions of one of the sections and have their other ends disposed in the tubular end portions of the other section. These ends of the T heads are externally threaded and have nuts 17 threaded thereon to bear against the 55

extremities of the end portions of said other section as best illustrated in Figure 2, so that upon turning of the nuts the frame sections are spread apart.

- 5 If desired, the T fittings 11 may be welded to both frame sections as shown in Figure 3. In this construction, the frame sections are forcibly spread apart by means of some suitable apparatus, and in Figure 3, the frame is shown as 10 having one of its sections engaged with a plurality of hooks 18 carried by a fixed support 19 and its other section engaged by hooks 20 carried by a movable tensioning member 21. The tensioning member 21 may be actuated in any desired manner as by a hydraulic ram 22.

In the assembly of this form of the invention, the frame sections are, of course, placed under tension before the T fittings are welded in place or at least before one section is welded to the 20 fittings, the welding being done while the frame sections are under tension.

Another method of making the frame is illustrated in Figures 4 and 5. In this embodiment, the frame sections 6' and 7' are of the conventional type having rounded corners 10'. T fittings 11 are employed as before to rigidly connect the two frame sections, but the perforated sheet 13' is attached to the frame sections entirely by welding. The inner wall of the frame 30 section may be slotted as at 23 to receive the adjacent marginal edge portions of the sheet as best illustrated in Figure 6.

In constructing this form of the invention, the T fittings 11 are first welded or otherwise fixed 35 to the end portions of one of the frame sections and then with the parts all loosely assembled, and the marginal edges of the sheet properly inserted in the slits of the frame sections, the two sides 8' of the frame are first welded to the sheet as illustrated in Figure 4. Then with the 40 sheet attached to the frame sections only at the sides thereof, the frame is placed in a stretching apparatus similar to that shown in Figure 3, and tension is applied tending to separate the two frame sections.

With the entire structure under tension, the remaining marginal edge portions of the sheet are welded to the corners and ends of the frame sections and also the T fittings are welded to the 50 other section.

In the embodiment of the invention shown in Figures 7 and 8, the frame is also of the type having rounded corners, but the perforated sheet is not welded thereto. To attach the sheet in 55 this construction, stamped metal corner fittings 24 are applied to the frame corners. These corner fittings 24, which are applied in a partially formed condition, have curved portions 25 to engage the corners of the frame sections and flat 60 webs 26 to overlie the opposite faces of the perforated sheet. In their partially formed condition, the corner fittings are slipped over the corners of the frame sections and then their webs 26 are forcibly brought together and riveted 65 in place with the adjacent corner portions of the sheet clamped therebetween. If desired, additional clips 27 may be provided at the sides of the frame.

As in the embodiment illustrated in Figures 70 4, 5, and 6, the T fittings in this form are welded to the end portions of the frame sections, and to insure a flat surface for the sheet, the sections are placed under tension during the final welding of the T fittings thereto.

75 The manner of using the frame is illustrated

in Figure 1. As here shown, the hide or skin to be stretched and dried is attached to the perforated sheet by attaching clips or toggles 28, which grip the edge of the skin or hide and hook into one of the perforations of the sheet.

From the foregoing description taken in connection with the accompanying drawings, it will be readily apparent to those skilled in the art to which this invention appertains, that a novel and improved construction for leather stretching and 10 drying frames has been provided, and that it insures a flat surface for the perforated sheet.

What I claim as my invention is:

1. A leather stretching frame unit comprising a distendable border frame having diagonal corner portions, a perforated metal sheet attached to the border frame by having its corners folded over the corner portions of the border frame, so that said corners of the sheet have a sliding engagement with the diagonal corner portions 20 of the frame, and means for distending and holding the frame distended so as to stretch the sheet both longitudinally and transversely.

2. A leather stretching frame unit comprising, a border frame composed of complementary sections having substantially diagonal corner portions, a perforated sheet, and means fixed to the corners of the sheet and having a sliding engagement with the diagonal corner portions for connecting the perforated sheet to the diagonal corner portions of the border frame so that forced separation of said complementary sections acting through the diagonal corner portions imposes a tension on the perforated sheet.

3. A leather stretching frame unit comprising 35 a substantially rectangular border frame composed of two complementary sections each having substantially diagonal corner portions, a perforated sheet, and means slidably engaged with the diagonal corner portions and fixed to the corners 40 of the sheet for connecting the sheet with the substantially diagonal corner portions of the frame sections so that forced separation of said frame sections imposes tension to the sheet in all directions.

4. A leather stretching frame unit comprising a rigid border frame composed of complementary sections having end portions and diagonal corner portions, a perforated metal sheet attached to the frame sections by having its corners folded over 50 and slidably engaged with the diagonal corner portions so that upon forced separation of the sections, said sheet is placed under tension, and supporting members for the frame secured to the end portions of the frame sections to rigidly 55 connect the frame sections and hold the same in their positions maintaining the sheet under tension.

5. A leather stretching frame unit comprising a border frame composed of complementary sections having substantially diagonal corner portions, a perforated metal sheet having its corners engaged over the substantially diagonal corner portions so that upon forced separation of the frame sections, the sheet is placed under tension, 65 and means to rigidly connect the frame sections and hold the same in their positions maintaining the sheet under tension.

6. A leather stretching frame unit comprising 70 a border frame composed of complementary sections having substantially diagonal corner portions, a perforated metal sheet having its corners engaged over the substantially diagonal corner portions so that upon forced separation of the 75

frame sections, the sheet is placed under tension, and substantially T shaped mounting members having the opposite ends of their heads secured to the frame sections to rigidly connect the same and hold the same in their positions maintaining the sheet under tension, the stems of said T shaped members forming trunnions to pivotally mount the frame unit.

5 7. A leather stretching frame unit comprising a border frame composed of complementary sections having end portions, a perforated sheet attached to the sections so that forced separation of said sections places the sheet under tension, means to rigidly connect the end portions of the sections, and means associated with said last mentioned means to forcibly spread the sections apart.

10 8. A leather stretching frame unit comprising a rigid border frame composed of complementary sections having aligned tubular end portions, a perforated metal sheet having opposite portions attached to the complementary sections so that the sheet may be placed under tension by forced separation of the frame sections, mounting members to pivotally mount the unit having opposite portions received in the adjacent aligned tubular end portions of the frame section, and screw means associated with the said mounting members to forcibly spread the frame sections apart.

15 9. A leather stretching frame unit comprising a stiff border frame composed of similar sec-

tions having aligned tubular end portions and substantially diagonal corner portions, a perforated metal sheet, means to attach the metal sheet to the substantially diagonal corner portions so that forced separation of the sections imparts tension to the sheet, substantially T shaped mounting members to connect the adjacent end portions of the frame sections, the opposite end portions of the heads of said T shaped members being received in the tubular end portions, means to fix one end portion of each head in its tubular end portion, and nuts threaded on the other end portions of the T shaped mounting members and bearing against the extremities of the other frame end portions whereby said nuts provide means for spreading the frame sections.

20 10. The herein-described method of making a leather stretching frame unit, which consists in aligning two similar substantially U shaped frame sections with their open ends in register with each other to form substantially a rectangle, loosely connecting the adjacent frame section ends by means of mounting members, securing opposite portions of a perforated sheet to the frame sections, applying stress to the frame members in opposite directions to stretch the sheet, and in fixing the frame sections to the mounting members in their positions maintaining the sheet under tension.
